Primary Examiner — Shannon W Morgan*Assistant Examiner* — Altaira J Swangin(74) *Attorney, Agent, or Firm* — Emerson Thomson Bennett; Daniel A. Thomson(57) **CLAIM**

The ornamental design for a nail clipper, as shown and described.

DESCRIPTION

FIG. 1 is a closed perspective view of the nail clipper;

FIG. 2 is a left view;

FIG. 3 is a right view;

FIG. 4 is a bottom view;

FIG. 5 is a top view;

FIG. 6 is a front view;

FIG. 7 is a rear view; and,

FIG. 8 is an open perspective view.

The broken lines show portions of the nail clipper, which form no part of the claimed design.
